UNITED STATES PATENT OFFICE.

HORATIO GATES, OF WORCESTER, MASSACHUSETTS.

REVERSIBLE PLOW.

SPECIFICATION forming part of Letters Patent No. 291,502, dated January 8, 1884.

Application filed March 10, 1883. (No model.)

To all whom it may concern:

Be it known that I, HORATIO GATES, of Worcester, in the county of Worcester and State of Massachusetts, have invented certain new and useful Improvements in Reversible Plows; and I declare the following to be a description of my said invention sufficiently full, clear, and exact to enable others skilled in the art to which it appertains to make and to use the same, reference being had to the accompanying drawings, which form a part of this specification.

The objects of my present invention are to provide an improved reversible plow that will work the furrows with the same facility as a landside-plow, and have the same relative lines of draft and equal tendency to run to land, whether working in right or left position of adjustment; to provide a simple mechanism for the automatic shifting of the clevis by the action of reversing of the plow; to afford means for conveniently and securely locking the plow at positions of right or left adjustment; to afford means for sustaining the backward strain of the share without undue strain upon the reversing-hinges; to provide a plow with a reversible colter or sod-turner adapted for swinging action on the beam for adjustment to right or left working position, and means for conveniently securing the same at either position of adjustment. These objects I attain by mechanism constructed substantially as shown in the accompanying drawings and herein described, the particular subject-matter claimed being hereinafter definitely specified.

In the drawings, Figure 1 represents a side view of a plow, illustrating the features of my invention. Fig. 2 is a bottom view of the beam, showing the devices for automatically shifting the clevis and for fastening the sod-plow in position. Fig. 3 is a rear view of one of the arms on which the shares and mold-boards are secured, showing the portion sustained against the forward standard and the triangular portion with hole for the fastening-rod. Fig. 4 is a top plan view of the hinging-plate for supporting the rocking arms. Fig. 5 is a transverse section through the beam and hinge-plate on larger scale. Fig. 6 is a transverse vertical section of the beam, showing the front of the main plow. Fig. 7 is a transverse vertical section, showing the front of sod-

plow. Fig. 8 is a side view of the landside and shoe on larger scale. Fig. 9 is a bottom view of the landside without the shoe. Fig. 10 is a transverse vertical section of the landside and shoe on larger scale. Fig. 11 is a view of a knife or blade for attachment to the front of plows.

In the drawings, A denotes the beam, and B the handles, of ordinary form. C indicates the landside, provided with standards *cc*, which are permanently attached to the beam A by bolts *a a*, and by which said landside is supported in stationary position centrally beneath the beam. The opposite faces of the landside C are of corresponding shape, so that it serves as a fixed landside for either of the reversing mold-boards and shares when brought down into working position for or when turning furrows either to the right or left. The bottom or foot of the landside C is provided with a longitudinal dovetailed or undercut groove, *b*, extending from its front end nearly to its rear end, and preferably made with a slight taper toward the rear, while the shoe or wearing-piece C' is provided with a rib, *b'*, of corresponding shape, which serves for attaching said shoe to the landside, the parts being put together by inserting the rib *b'* into the groove *b* from the front end and forcing it backward until the end of the rib strikes the end of the groove, which prevents all further backward movement of the shoe. When the shoe becomes worn out, it can be readily removed or driven out by striking it with a hammer on its rear end, and a new shoe inserted in its place. If preferred, the groove *b* may be formed in the shoe *c*, and the rib *b'* may be formed on the bottom of the landside C, the parts being fitted and retained together in substantially the same manner as above described. The plow is made with two mold-boards, D D', with shares F F', respectively connected in reverse and diametrically-opposite positions to rocking arms E E', which are hinged to the beam A in such manner that either mold-board D or D' can be turned down into position against the stationary landside C (one at the right the other at the left) to form in connection therewith a complete plow having substantially the same shape and relative draft alignment as an ordinary single or landside

plow. When one mold is down in working position, the other one is elevated above the beam, or vertically over the first, as indicated in Figs. 1 and 6. The arms $E E'$ swing or rock over the top of the beam to effect the change from right to left, and vice versa. The rocking arms are made substantially straight laterally and provided with offset hinges e , pivoted between ear pieces or bearings e' , formed on a hinge-plate, G , that is attached to the top of beam A , as shown. In case the plow-beam A is made of iron the hinge-ears e can, if desired, be cast integral with the beam, and also the lugs h could be formed on the sides of the beam integral therewith. The hinge-plate is in the present instance made from cast-iron, of the form shown, and it is connected to the beam by the same bolts, a , which secure the landside-standards c to the beam. Said plate G is provided with side guards, g , which form seats for the arms when down, and with lugs or flanges h , that form back supports for the arms $E E'$, to assist in sustaining any backward strains that may be brought to bear on the hinges.

I prefer the form of hinge and plate G shown, but do not desire to confine myself to this identical construction, as the hinge may be made or arranged in different form, and a plate G may be used without the side guards, g , and lugs h ; or the plate may be formed in two parts—one for each arm—instead of being made integral, without departure from the nature of my invention.

The outer ends of the arms $E E'$ are properly shaped to support the mold-boards $D D'$, to which they are connected by bolts or other suitable fastenings. The main arm E has its ends widened and shaped to proper form to receive and support the plow point or share F , and to fill the triangular space in front of the landside and beneath the point. Said arm E is formed with a shoulder or offset, f , which fits over the front of the landside and forward standard c , so that the strain or draft is transferred from the beam to the plow through the standard c , and little, if any, strain is brought onto the hinging of the arms. The mold-boards $D D'$ are preferably made from sheet-steel bent to a cylindrical curve, but can be otherwise formed, if desired. The points or shares F can be made of sheet-steel, or be cast from iron or steel. The mold-boards and shares are retained in working position by means of a bolt or rod, H , which passes through a longitudinal opening in the landside-casting and enters a hole, i , in the triangular portion of the rocking arm E , as indicated. The rod H is connected with the lower end of a lever, I , fulcrumed on the rear standard c , and having its upper end, which is provided with a suitable handle, located at a convenient position to be reached by the attendant, who can lock and unlock the reversing mold-boards from the stationary landside C by swinging the lever I forward or back, as required. The point of the plow may be provided with an in-

clined lug or projection, m , for guiding the parts onto each other and preventing the angle at f from striking the forward angle of the standard c in case there is any looseness or backlash in the hinging. A reversing colter, jointer, or sod-plow, K , is attached to the beam forward of the main plow, and arranged for reversal in similar manner by swing-arm E^3 , hinged to the top of the beam A , as indicated at G^3 . The arm E^3 is offset or bent, similar to illustration, Fig. 7, to bring the sod-plow K into proper working alignment beneath the beam A . The colter or sod-plow is retained in adjusted position by a rod, J , the forward end of which is provided with two hooks, n , which engage the arm E^3 at either side of the beam A for drawing it close to the side of the beam, while the rear end of the said rod is connected with the lever I , so that the sod-plow K is secured and released at the same time and by the same movement that operates the fastening devices of the main plow. If desired, the arms E and E^3 can be connected with each other in such manner that the plow K will swing or reverse in unison with the mold-boards $D D'$. A plate having side projections, L , is secured to the under side of the beam in position to receive the backward strain of the plow or colter K , the arm of which rests against the forward side of the projection L when the plow is down in working position. The plate L also forms a guide for the rod J , and may also serve for a fulcrum-bed for the clevis-operating lever.

Figs. 1 and 2 illustrate my improved device for shifting the clevis M automatically when the plow is reversed. The lower part of the clevis is extended backward from the retaining-bolt o to engage with a lever, N , the fulcrum of which is on the under side of the beam at P . A second lever, R , fulcrumed at S , extends backward to a position where its rear end will engage with the forward part of the mold-boards $D D'$ or shares $F F'$, so that the lever will be pressed toward one side or the other, accordingly as the plow is adjusted for right or left hand furrows. The ends of the levers and the clevis-bar are connected by semicircular forks and rounded heads, as shown, or in other suitable manner, so that the action of the lever R will be transmitted to swing the clevis to the right or left, thereby changing the line of draft relatively to the axis of the beam for causing the plow to take land either on the right or left, according with the right or left adjustment of the mold-boards $D D'$. If desired, the ends of the two levers N and R may be extended past each other and longitudinally slotted at their junction and be connected by a movable stud, so that the throw of the clevis can be regulated to give a greater or less degree of side draft, when required, by simply changing the position of the connecting-stud within the slots relatively to the fulcrums of the levers. This arrangement of levers for operating the clevis automatically can be used in connection with reversible plows of

other construction than that herein shown with beneficial results, and I desire to include such use of the device as within the scope of my invention.

5 The plow may be made and used either with or without the reversing sod-plow or colter, as preferred. It may, also, be made with or without the device for automatically shifting the clevis.

10 T indicates a thin sharp blade of steel for attachment to the front of the sod-plow (or to the main plow, in case the sod-plow is not employed) for cutting the sod on the line of division of the furrows. Said blade may be slotted for the holding-screw in the manner indicated, so that the blade can be set forward as its edge is worn away. Said blade T can be readily detached from the plow for sharpening when it becomes dulled by use.

15 20 I am aware that plows have heretofore been made in which reversal for right and left operations is effected by swinging two connected plows about a longitudinal axis; and I do not therefore herein broadly claim such method of reversing a plow. So far as I am aware, however, such plows have not been heretofore made as herein shown and described.

25 I am also aware that devices have heretofore been employed for shifting the clevis of a 30 plow; and I do not therefore broadly claim a shifting-clevis irrespective of the construction of the mechanism for effecting its operation.

What I claim as of my invention, and desire to secure by Letters Patent, is—

35 1. A swivel or reversible plow having two mold-boards, D D', connected together by rocking arm E' and rocking arm E, provided with triangular pieces E², in combination with the hubs or bearings e' on the top of the beam, and 40 means for retaining either of said mold-boards at working position, substantially as set forth.

45 2. A swivel or reversible plow having two mold-boards, D and D', rigidly connected at diametrically-opposite positions by the rocking arms E and E', which are hinged to hubs or bearings on the top of the beam A, in combination with the fastening-rod H, which passes through the landside C into the triangular end of the arm E, and the lever I, adapted for simultaneously operating the fastening-rod H and the fastening-rod J, substantially as shown and described.

50 3. In combination with a swivel or reversible plow, the reversible jointer or sod-plow K, having two small mold-boards connected by

the rocking arm E³, which is hinged to the hubs or bearings G², in combination with the beam A, substantially as shown and described.

4. A swivel or reversible plow having two mold-boards, D D', connected together by rocking arms E E', hinged to hubs or bearings on the beam A, in combination with two jointers or sod-plows, K, connected by swinging arms E³, hinged to hubs or bearings G² on the top of the beam, and devices for simultaneously fastening and releasing said mold-boards and sod-plows, substantially as described. 60 65

5. In combination with a swivel or reversible sod-plow or jointer, the fastening-rod J, hinged to the lever I and passing forward at 70 the under side of the beam A, with its forward ends provided with hooks n for fastening the sod-plow or jointer firmly in working position at either side of the beam, substantially as shown and described. 75

6. In a swivel or reversible plow, the arm E, which connects the mold-boards D D' and shares F F', provided with the offset or lip f, in combination with the forward landside-standard e, as and for the purpose set forth. 80

7. In a swivel or reversible plow having two mold-boards connected by rocking arms E E', the hinge-plate G, provided with side guards, g, and supporting lugs or ribs h, substantially as and for the purpose set forth. 85

8. In a swivel or reversible plow having two mold-boards connected by rocking arms hinged to the top of the beam, the plate carrying the ears or bearings e', adapted for attachment to the wood beam A by the same bolts which secure the standards of the stationary landside C to said beam, as shown and described. 90

9. The combination, with the beam A and reversing sod-plow K, of the supporting-plate provided with projections L, and adapted to 95 serve as a guide for the rod J and fulcrum-bearing for the lever R, substantially as shown and described.

10. The combination, with the clevis M, having an arm extending backward from its pivoting-bolt, of the levers N and R, fulcrumed on the beam A and arranged for operating in connection with the plow, in the manner shown and described. 100

Witness my hand this 6th day of March, A. 105
D. 1883.

HORATIO GATES.
